CLAIM

The ornamental design for a removable ground cover to
catch shrub clippings, as shown and described.

DESCRIPTION

FIG. 1 is a top plan view of a removable ground cover
to catch shrub clippings showing my new design;

FIG. 2 is a side elevation view thereof;

FIG. 3 is a sectional view thereof taken along the line
3—3 of FIG. 1; and

FIG. 4 is a perspective view thereof shown in operative
condition on a reduced scale.

FIG. 1

FIG. 2

FIG. 3

FIG. 4
